(57) **CLAIM**

The ornamental design for a nasal mask assembly, as shown and described.

DESCRIPTION

FIG. 1 is a perspective view of a nasal mask assembly showing our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of portions of the nasal mask assembly is included for the purpose of illustrating an internal boundary of the design, with lines themselves and the area within, forming no part of the claimed design.
